(57) **CLAIM**

The ornamental design for a coffee brewer as shown and described.

DESCRIPTION

FIG. 1 is a front isometric view of a coffee brewer showing the new design.

FIG. 2 is a left side isometric view thereof.

FIG. 3 is a front elevation view thereof.

FIG. 4 is a left side elevation view thereof.

FIG. 5 is a rear elevation view thereof.

FIG. 6 is a right side elevation view thereof.

FIG. 7 is a top plan view thereof.

FIG. 8 is a bottom plan view thereof; and,

FIG. 9 is a front isometric view thereof with an environmental coffee carafe removed therefrom.

The shade lines in the Figures show contour and not surface ornamentation. The broken lines in the Figures show portions of the coffee brewer and surrounding environment that form no part of the claimed design.
